CLAIM

The ornamental design for a bracket assembly, as shown and described.

DESCRIPTION

FIG. 1 is a top front perspective view of the bracket assembly showing my new design;

FIG. 2 is a top view thereof;

FIG. 3 is a bottom view thereof;

FIG. 4 is a back view thereof;

FIG. 5 is a front view thereof;

FIG. 6 is a left side view thereof;

FIG. 7 is a right side view thereof;

FIG. 8 is a bottom front perspective view in an environment; and,

FIG. 9 is a bottom perspective view thereof in an alternate position of use.

The broken lines are included for the purpose of illustrating the design in an environment and form no part of the claimed design.
